UNITED STATES PATENT OFFICE.

HARRY KING RAYMOND, OF AKRON, OHIO, ASSIGNOR TO THE B. F. GOODRICH COMPANY, OF NEW YORK, N. Y., A CORPORATION OF NEW YORK.

DESIGN FOR A PNEUMATIC TIRE.

50,915.

Specification for Design.

Patented June 12, 1917.

Application filed April 12, 1917. Serial No. 161,666. Term of patent 14 years.

To all whom it may concern:

Be it known that I, HARRY K. RAYMOND, a citizen of the United States, residing at Akron, in the county of Summit and State of Ohio, have invented a new, original, and ornamental Design for Pneumatic Tires, of which the following is a specification, reference being had to the accompanying drawings, forming a part thereof.

Figure 1 represents a plan view of a

pneumatic tire extended or flattened out and bearing my new design.

Fig. 2 represents a cross section of the tire wall in its normal shape, taken on the line 2—2 of Fig. 1.

I claim:

The ornamental design for a pneumatic tire as shown.

HARRY KING RAYMOND.
